(57) **CLAIM**

The ornamental design for a mobile air conditioning kit, as shown and described.

DESCRIPTION

FIG. 1 is a first perspective view of a mobile air conditioning kit showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion in FIG. 1. The broken lines shown in the drawings depict portions of the mobile air conditioning kit in which the design is embodied that form no part of the claimed design.
